UNITED STATES PATENT OFFICE.

FERDINAND FANTA, OF LONDON, ENGLAND.

MANUFACTURE AND REPAIR OF INCANDESCENT ELECTRIC LAMPS.

SPECIFICATION forming part of Letters Patent No. 683,558, dated October 1, 1901.

Application filed May 26, 1900. Serial No. 18,154. (No specimens.)

To all whom it may concern:

Be it known that I, FERDINAND FANTA, a subject of the Queen of Great Britain and Ireland, residing at London, England, have 5 invented a new and useful Improvement in and Relating to the Manufacture and Repair of Incandescent Electric Lamps, (for which I have made application in Great Britain under No. 21,966, bearing date November 2, 1899; 10 in France under No. 288,125, bearing date May 2, 1900, and in Belgium under No. 118,170, bearing date May 2, 1900,) of which the following is a specification.

The object of this invention is a mode of 15 treatment for increasing the life of electric incandescent lamps by renewing or regenerating the incandescent filaments of the same when their efficiency has become too low while fixed in their sockets and leads and in 20 the globe in which they are to be used as lamps, thus reducing the original outlay or cost of those lamps to a considerable extent.

As is well known the passage of current 25 through the filament in use as a lamp results in a part of such filament volatilizing, the particles of carbon thus volatilized attaching to the inner surface of the bulb, whereby the same is obscured, while the resistance of the filament is increased considerably. The lighting 30 efficiency of the lamp thus decreasing rapidly, the same has soon to be discarded altogether. I am aware that attempts have been made to use the bulbs of such "burned-out" or "spent" lamps over again; but in all 35 instances the inventors have suggested the withdrawal of the old filament. It is obvious that this is a costly and in most instances more difficult process than the manufacture of the original lamp, and the principle is, 40 moreover, at fault, as shown by the following considerations, which I have ascertained experimentally.

It has hitherto been believed that the whole body of the filament volatilizes or burns away 45 and loses in value in regard to its transmitting and lighting efficiency and that the "core," so to say, of the filament is destroyed; but I find that this is not the case, but, on the contrary, that the core or body of such filament 50 is after having been in use for several hun-

dred hours in a far better condition than when originally inserted into the lamp. This is accounted for by the fact that the original carbonizing process which the filament has to undergo before its insertion into the bulb 55 is performed too rapidly, and, further, that the process known as the "reinforcing" or "flashing" of the filament is carried out under unsatisfactory conditions, and these conditions are in most instances entirely at 60 variance with those under which such filament comes into use in the finished lamp. The result of this is that when the filament is used, as it is in actual practice, in a more or less perfect vacuum, and owing to the atmospheric air (which is still retained or imprisoned in the pores of the filament) becoming available for combustion the outer coating of carbon of such filament slowly combines with the same, and the CO vapors thus 65 formed deposit on the inner surface of the glass bulb, which acts in the fashion of a condenser. In order to again render serviceable 70 an electric incandescent lamp which has reached the above-described stage, it is therefore indispensable, first, to free the bulb of such carbon deposit, and, secondly, to redeposit carbon on the partly burned or spent filament.

The object of this invention is to accomplish 75 both these operations without removing the filament from the lamp, and consequently without interfering with the bulb, seal, or the capping of the lamp.

For carrying out the invention I first of all 80 remove or cut away the small protruding point of glass formed on the bulb of the lamp as originally made, when the tube by which the vacuum has been made therein is removed by means of the blowpipe, and I fix onto the 85 bulb instead of the point just broken off a small glass tube from four to six inches long. I thereafter heat the bulb outwardly and preferably locally by a flame applied successively over the surface to such a degree as 90 may be necessary to burn the carbon deposited on its inner surface, and this operation is facilitated and rendered practicable at temperatures not injurious to the integrity of the 95 glass and the preservation of the capping and 100

the filament by my causing previously-heated air to circulate freely in the bulb while simultaneously drawing off the gases resulting from the combustion by means of a pump or of 5 any other aspirating apparatus.

The annexed drawings show in Figure 1, as a vertical section, a practicable device for effecting the above circulation. Fig. 2 shows a diagrammatic arrangement of a number of 10 lamps in position for treatment, and Fig. 3 shows diagrammatically an arrangement of circuits and resistances during regeneration.

The tube *a* of the globe, which I use for the above purpose, is fixed gas-tight by a stuffing-box *b* and gland *b'* in a casing *c* and carries an inner tube *i*, the extremity of which is long enough to reach the part of the bulb diametrically opposite to the portion of the bulb into which the outer tube *a* is jointed. The inner 15 tube *i*, which is also fixed gas-tight in a lower stuffing-box *e*, is then used for the introduction of the atmospheric air from the flange-opening *f* or *h*, controlled by a two-way cock *d*, while the outer tube is connected to a pump 20 through the side orifice *g*, also controlled by a cock, and provides means for withdrawing the gases resulting from the combustion of the carbon deposit. After a short period of 25 application of this cleansing process the glass of the bulb appears quite clear and free of the carbon. The bulb is now ready, and the process of depositing carbon on the filament can be proceeded with. For this purpose, having created as perfect a vacuum as possible 30 in the bulb, I introduce into the bulb by mechanical circulation under pressure controllable as to required reduced pressure in bulb a gaseous hydrocarbon (as gasified liquid hydrocarbon or, more conveniently, purified 35 coal-gas) with an admixture of a certain quantity of free atmospheric air, the proportion or percentage of which varies in accordance with the voltage and the candle-power of the filament and the condition of the vacuum in the 40 lamp to be treated, as stated hereunder. I then pass the electric current through the filament. The introduction of the gaseous admixture can be effected by means of the above-referred-to inner tube *i* by one of the alternative passages *f* and *h*, controlled by a two-way cock *d*, and the withdrawal of the gases resulting 45 from the slow combustion brought about by the incandescence of the filament caused by the passage of the electric current is effected 50 by means of the pump through the side exit *g*, the pressure of the gaseous mixture in the bulb being carefully regulated and maintained by means of adequate pressure-regulating valves or other automatic devices, it 55 being essential to the success of the process that such pressure be adjusted to the condition of the filament in relation to the voltage of current and the candle-power required from the filament, as also to the size of the 60 containing-bulb, as more particularly defined 65

hereunder. As a result of this process carbon deposits on the filament, and it is obvious the resistance of the same diminishes, while the candle-power increases. Since, on the other hand, the object is to restore the 70 carbon filament to its original smaller resistance and higher candle-power, I begin my operation with a variable resistance *k*, Fig. 3, inserted in the main regenerating-circuit *l*, and I gradually increase this resistance 75 simultaneously with the deposit of carbon upon the filament to compensate for the increasing section and reduced resistance of the filament and use a photometer *p*, Fig. 3, for the purpose of standardizing the required lighting efficiency of the reinforced filament in comparison with a standard lamp or source of light *m* on a separate constant circuit *n* and with a required voltage of current on the regenerating-circuit *l*, maintained at a 80 constant calculated voltage by the variable resistances *k*. I stop the operation when the voltage and the candle-power indicated by the instruments have reached the desired point—viz., when the resistance, and consequently the candle-power of the filament have 85 been brought back to their former value in the original lamp or to a predetermined or required standardized value. Allowance should, however, be made for the fact that 90 the resistance of the filament when in vacuum is less than that of the filament immersed in the gaseous mixture, and consequently the normal voltage of the finished lamp when sealed *in vacuo* will be considerably lower 95 than that appearing during the time of finishing or flashing the same in the gaseous mixture and while the lamp is unsealed—*i. e.*, the voltage of the regenerating-circuit *l*, Fig. 100 3, is at a much higher and calculated voltage 105 than the voltage of the ultimate working circuit on which the lamp is designed to be eventually used when sealed *in vacuo*. When the process has been completed to this point, the bulb is exhausted and sealed in the usual 110 well-known manner.

I find that the proportion of atmospheric air of the gaseous mixture, which is important to prevent deposit of carbon on the glass, should vary from three to ten per centum, 115 according to the nature or condition of the filament to be “flashed,” the percentage of the air being smaller for filaments of low candle-power than for filaments of higher candle-power—*i. e.*, for a filament of sixteen candle-power a percentage of five of air will be suitable for a uniform filament; but with a burned filament of irregular section, of poor condition, the percentage of air must be kept at the above lowest value until the filament 120 has been reinforced at its weakest parts, when the percentage of air may be increased. The quantity of air used is also dependent on the efficiency of the pump used, *viz.* The proportion of air forming part of the gaseous 125 130

mixture may be smaller when powerful pumps (pumps which are capable of drawing off large bulk of gases) than when less powerful pumps are used, for where a vacuum-pump 5 of poor efficiency is used it is obvious a proportion of air will remain in the bulb, and therefore a less quantity of air must be introduced. The pressure of the gaseous mixture in the bulb above the best vacuum obtained by the vacuum-pump may vary from 10 four to fifteen millimeters of mercury, according to the dimensions of the bulb, the section of the filament, and the condition of the latter. Filaments of poor efficiency and 15 those of high resistance require more pressure than those of better efficiency and those of low resistance—as, for instance, a partly-burned or irregular filament of high resistance in whole or in part must be regenerated 20 at first at the highest of the above pressures, and as the filament becomes uniform the pressure may be reduced and the deposit of carbon thus diminished by reduction of pressure up to the point of above lowest pressure 25 when nearing the point of standard or required section or resistance.

The above variations of pressure and percentage of air must be left to the skill and observation of the operative upon the above 30 generally-indicated principles to prevent burning or deflagration of a worn, irregular, or poor filament, as in the matter of repair no two are alike in condition when regeneration is first commenced. The same filament 35 will require less pressure in the bulb when treated in a large than in a smaller bulb in order to give better advantage to the mechanical pressure of supply of the gas (which is much higher than the above pressures used 40 in the bulb) to produce a more vigorous circulation through the larger bulb than is necessary in the smaller bulb. I further wish it to be understood that since the present invention shows a method to flash the filament 45 in the actual bulb in which it is to be used, owing to my preventing sooty carbonaceous matter from being formed and depositing on the containers during the flashing process, (owing to my using an appropriate percent- 50 age of atmospheric air,) this process would advantageously replace the mode of finishing or flashing the filaments previously to their insertion into the bulb of the lamp, and also I wish it to be understood that the simultaneous use of the photometer as described herein during flashing and before the sealing of the bulb provides means not only of ascertaining and adjusting the efficiency of the filament most accurately, but also (and this 55 is most important) to reduce to a very large extent, if not to do away altogether with, the large percentage of "odd voltages" of the lamps as now resulting from the mode of manufacture commonly used by incandes- 60 cent-electric-lamp makers.

Having now described this invention, what I claim, and desire to secure by Letters Patent, is—

1. A process for the regeneration and reinforcement of the carbon filaments of incandescent electric lamps, while fixed "in situ" 70 in the lamp-globes in which they are to be eventually used, consisting in making access to the upper part of the globe; removing the air from the globe; mixing air and a hydrocarbon gas, within the limits of variable proportion as specified; circulating mechanically under controlled pressure the said mixed gases through the said globe, from one end to the other; passing an electric current through 75 said filament while said circulation is in progress; stopping the current when filament is standardized; exhausting the residual hydrocarbon gas from the globe without admission of the atmosphere; and finally sealing the 80 globe, substantially as specified.

2. In a process for the regeneration and reinforcement of the carbon filaments of incandescent electric lamps, while fixed "in situ" 85 in the lamp-globes in which they are to be used, continuously circulating a mixture of air and hydrocarbon through the said globe, while an electric current is passing through the said filament, substantially as specified.

3. In a process for the regeneration and reinforcement of the carbon filaments of used incandescent electric lamps, circulating into the said globe previously-heated air, and withdrawing therefrom products of combustion, simultaneously with the application of moderate external heat to clean and prepare the globe of the lamp for the regeneration and reinforcement of the filament, substantially 95 as specified.

4. In a process for the regeneration and reinforcement of the carbon filaments of incandescent electric lamps "in situ" in the lamps 100 in which they are eventually to be used, regulating mechanically the pressure and the proportions of the mixed hydrocarbon gas and air, while the same is circulating through the globes of the said lamps, to suit the condition and candle-power of the filament, and the size of the globe, substantially as specified.

5. In a process for the regeneration and reinforcement of the carbon filaments of incandescent electric lamps, the mode of standardizing the filament "in situ" in the globe in which it is to be eventually used, before sealing the same, consisting in passing a mechanically circulated and controlled stream of mixed air and hydrocarbon gas uniformly over said filament, (in order to avoid an obscuring deposit on inside of globe and to avoid burning a weak or poor filament); passing an 110 electric current, of predetermined excess value above that at which the lamp is to be worked *in vacuo*, through said filament in said mixed vapor; controlling said current at 115 desired voltage by variable added resistances, 120

125 130

to compensate for the resistance of reinforcing filament; estimating by the photometer the required incandescence of the filament under said controlled and definite electric current; determining the cessation of the reinforcing process by photometric test; exhausting the residual hydrocarbon vapor from the globe; and the sealing of the globe "in situ" without admission of the atmosphere to the

globe, and without disturbance of filament connections, to form a complete standardized lamp, ready for use, substantially as specified.

In witness whereof I have hereunto set my hand in presence of two witnesses.

FERDINAND FANTA.
